DELAYED CONTROL TIMELOCK

William C. Miller and Paul M. Hawkins, Canton,
Ohio, assignors to Diebold Safe & Lock Co.,
Canton, Ohio, a corporation of Ohio

Application September 8, 1933, Serial No. 688,692

2 Claims. (Cl. 70—26)

This invention relates particularly to a delayed control timelock which is equipped with means for preventing the opening of a safe door until a predetermined time has elapsed after the combination has been set for unlocking. The broader phases of the invention are, however, applicable to control timing mechanism used in other combinations. In many respects, the invention constitutes an improvement upon Miller and Kuenzel application, Serial No. 613,954, for Delayed control timelock.

In delayed control timelocks employing clockwork, it has been found that jarring or other effects sometimes causes the escapement of a clockwork to catch or bind, with the result that considerable difficulty and expense is encountered in opening the safe.

An object of the present invention is to provide timing mechanism with two or more escapements and with interconnecting means between the escapements so that one may function to control the clockwork even though the others become inoperative. A further object is to provide a delayed control timelock which is automatically wound and placed in operation by the setting of the combination for opening the safe, the timelock being provided with a pair of escapements joined by differential gear connections so that if one escapement does not work, the other will function as a control of the clockwork. Other specific objects and advantages will appear as the specification proceeds.

The invention is illustrated, in a preferred embodiment, by the accompanying drawings, in which—

Fig. 1 is a plan view of a timelock embodying our invention, the timelock being shown applied to the wall of a safe door; Fig. 2, a view taken as indicated at line 2 of Fig. 1; Fig. 3, a view taken as indicated at line 3 of Fig. 1; Fig. 4, a detail end view of the winding mechanism and winding gear; Fig. 5, a rear view of the clockwork showing the index gear; Fig. 6, a top plan view of the timing mechanism; Fig. 7, a broken detail view in elevation of one of the escapements employed; and Fig. 8, a longitudinal sectional view of the differential gear connections between the escapement devices.

In the illustration given, A and A' represent the two-part casing which houses the operating mechanism; B represents a combination lock apparatus which is enclosed by casing A; and C represents the clockwork within casing A'.

The casing parts A and A' may be of any suitable construction and may be secured by screws

or other suitable means. In the illustration given, the casing A is provided on one side with a slot 10 through which a locking bolt 11 extends.

The combination lock may also be of any suitable construction. In the drawings, a combination lock of a standard or well-known design is illustrated. The lock is provided with the usual operating spindle 13 which extends through the safe door and carries the operating knob 14. The knob is equipped with the usual dial 15. Upon the spindle 13 are mounted, in the usual manner, a series of notched tumblers 16. Keyed to the inner end of spindle 13 is the bolt operating disk 17. The disk 17 is provided with a notch 18 arranged to receive the lug 19 upon the bolt slide 20, the pin 21 upon the lever 20 being arranged to enter the notches of the safe tumblers when the notches are brought into alignment. In view of the fact that the combination lock illustrated is well known, further detailed description will not be necessary.

The combination lock mechanism B differs from the standard design only in two particulars. The operating disk 17 carries a curved member 22 which is eccentrically and pivotally mounted on disk 17. The member 22 has at its forward end, a long curved arm 23, and at its rear, a short arm 24, the rear arm 24 being slotted to engage a spring 25 which is secured by posts 26 to the disk 17. The rear arm 24 of the member 22 is adapted to engage a fixed post 27 on disk 17. The member 22 is employed for winding the main spring of the clockwork as will be described more in detail hereinafter. Secured to the bolt slide lever 20 near the point of its pivotal connection with bolt 11 is a fixed metal post 28. The post 28 cooperates with means hereinafter described for preventing the withdrawal of the bolt until a predetermined time has elapsed after the setting of the combination for unlocking.

The clockwork C may also be of any suitable construction. The winding gear 29 is connected by pinion 30 to a gear 31 fixed to shaft 32. The shaft 32 carries a main spring not shown, but housed within casing 33. The shaft 32 carries at its rear end a pinion 34 which drives an index gear 35 pivotally mounted on the rear frame wall of the clockwork. The index gear 35 is provided with a plurality of threaded openings 36 on one side of the gear, and a similar series of spaced openings 37 at the other side of the gear. Threaded pins 38 and 39 are adapted to engage openings 36 and 37, respectively, as illustrated more clearly in Fig. 5, the pin 39 being adapted to engage an actuating lever arm 40, and the

other pin being adapted to engage a stop 41 carried by the rear wall of the clockwork frame. The lever arm 40 is fixed to shaft 42 rotatably mounted in the clockwork frame. To the other 5 end of the shaft 42 is fixed an arm 43 having a reduced end portion 44 received within the slotted end 45 of the pivoted detent or guard 46. As shown more clearly in Fig. 6, the guard 46 has its inner end 47 pivotally mounted on stud 10 48. The lower front portion 49 of the guard 46 is adapted to engage the pin 28 on bolt-withdrawing arm 20, and thus to prevent the bolt from being retracted. The rotary movement of shaft 42, however, which lifts the arm 43, raises guard 15 46 so as to move it away from obstructing position with respect to pin 28. A spring 46^a normally urges the guard 46 toward its lower or obstructing position.

The index gear 29 is provided with a fixed 20 pin 50 which is adapted to be engaged by the member 22 carried by the operating disk 17 to wind the clockwork. The axis of rotation of disk 17 is eccentric to that of index gear 29 whereby arm 23 will engage pin 50 and rotate gear 29 25 for a part of the revolution only of the disk, as shown in Fig. 4.

In our improved clockwork and, as shown more 30 clearly in Figs. 6, 7 and 8, we provide a pair of escapements joined by differential gear connections so that when one escapement is rendered 35 inoperative, the other may continue to function as a control for the clockwork. A rotatably mounted shaft 51 carries a pinion 52 secured thereto. A pair of gears 53 and 54, equipped with 40 collars 53^a and 54^a, respectively, are freely mounted on shaft 51, as shown more clearly in Fig. 8. Between the collars 53^a and 54^a, is mounted a block 55 which is fixed to shaft 51. To the upper 45 side of block 55 is pivotally mounted a small gear 56, the gear 56 being in a plane substantially at right angles to gears 53 and 54. As shown more clearly in Fig. 6, the collars 53^a and 54^a are provided on their inner sides with a circular row of teeth 57 meshing with the teeth of 50 gear 56. To hold the assembly together in proper position, a collar 58 may be fixed to shaft 51 adjacent gear 54 and its collar 54^a. Escapement devices 59 are connected to each of the gears 53 and 54. In view of the well known construction of the escapements, a detailed description 55 will not be given.

In the operation of the mechanism, before the safe door is closed, the operator determines the 55 period of delay by placing the pin 38 in one of the openings 36, and the pin 39 in a corresponding and diametrically opposed opening 37. Preferably, the gear 35 is provided with numbers adjacent the openings to indicate the period of delay. The safe door may then be closed and 60 locked by scattering the tumblers. When it is desired to unlock the safe, the combination is set for unlocking, the setting operation serving to wind the clockwork. Referring to Fig. 2, when the disk 17 is turned in clockwise direction, the arm 23 of the winding member 22 slips under the pin 50 of winding disk 29. However, when the disk 17 is moved in counter-clockwise direction, the end of arm 23 engages the pin 50 and moves it a certain distance until the arm 23 clears the pin, due to the off-center mounting of the spindles 13 and 32 with relation to each other. This movement of pin 50 and gear 29 serves to 65 wind the main spring. The dialing is continued 70 until the notches of the tumblers are aligned and

pin 21 drops into the notches. This allows the lug 19 of the bolt-retracting arm 20 to enter the notch 18 of the operating disk 17. The combination lock mechanism is now in position to retract bolt 11. However, the retraction of bolt 5 11 is prevented by engagement of pin 28 with guard 46 which is held in lower or obstructing position by spring 46^a. The bolt therefore cannot be withdrawn until the clockwork has run the predetermined length of time. The index gear 10 35 is slowly rotated by the timelock mechanism until pin 39 engages the lever arm 40 and turns shaft 42. The rotation of shaft 42 swings arm 43 in an upward direction and raises the pivoted guard 46 until it clears pin 28. The bolt may 15 then be retracted in the usual manner.

In the operation of the escapement mechanism, the shaft 51 is driven by the chain of connecting gears between the main spring and pinion 52, and the gears 53 and 54 operate together with 20 their respective escapements. Should one of the escapement devices, for any reason, become inoperative, its respective collar will remain fixed, the shaft 51 turning freely therein. The horizontal gear 56, however, will permit the other 25 collar to rotate freely in connection with its escapement. It will be observed that either of the escapement devices may stop without affecting the operation of the other escapement and its 30 respective gear collar.

While in the foregoing illustration, we have 35 described the differential gear and double escapement in combination with a delayed control timelock, it will be understood that the mechanism may be employed with other types of clockwork or control timing mechanism. Also, while in the embodiment illustrated, the bolt, after the "setting" of the combination, is ultimately withdrawn (after retraction of the auxiliary guard, or detent) by further operation of the combination lock, it 40 should be understood that the invention is not limited to such specific embodiment, but is applicable to various embodiments, regardless of the specific character of the means employed for effecting the ultimate retraction of the bolt, or 45 boltwork, which locks the door to the jamb.

The foregoing detailed description has been 50 given for clearness of understanding only, and no unnecessary limitations should be understood 55 therefrom, but the appended claims should be construed as broadly as permissible, in view of the prior art.

We claim:

1. A lock comprising a bolt, auxiliary guard 55 means for preventing withdrawal of the bolt, normally idle clockwork arranged to operate upon winding and after operation for a time to release said guard means, a combination lock mechanism, means operated by the setting of the combination 60 for winding said clockwork, said last mentioned means comprising a bolt-operating disk carried by said lock mechanism, an arm connected by a pivot at an intermediate point to said disk and eccentrically thereof, a spring having one end 65 fixed to said disk and the other secured to said arm, and a spring-winding gear eccentrically mounted with respect to said disk and equipped with a post adapted to be engaged by said arm on said operating disk when the disk is rotated in one direction.

2. A lock comprising a bolt, guard means for preventing withdrawal of the bolt, normally idle clockwork arranged to operate and after operation for a time to release said guard means, a com- 75

5
bination lock mechanism, means operated by the manipulation of the combination lock for winding said clockwork, said last-mentioned means comprising an operating disk carried by said lock mechanism, an actuating arm pivotally connected to said disk, a stop, a spring urging said arm against said stop, and a spring winding gear ec-

centrically mounted with respect to said disk and equipped with a post adapted to be engaged by said curved arm on said operating disk when the disk is turned in one direction.
